PATRICK T. McLAUGHLIN AND WILLIAM ANDERSON, OF MIAMI, OKLAHOMA.

SAFETY BLASTING CARTRIDGE.

Application filed October 15, 1925. Serial No. 62,582.

This invention relates to a safety cartridge for dynamite or other high explosive which has to be exploded by a detonating cap, and particularly to a cartridge so constructed as 5 to permit the ready insertion of the cap within the stick of dynamite or other explosive and the ready insertion of the fuse therein, the device being so formed that the detonating cap will under no circumstances 10 come in contact with the bore of the hole and, therefore, will not be detonated accidentally.

It is the common practice today in the use of dynamite or other high explosive cartridges, to insert the cartridge within the 15 hole with the detonating cap disposed at that end of the cartridge which is inserted first into the hole, the fuse extending around the side of the cartridge and then out of the 20 hole and the opposite end of the cartridge being formed with a longitudinally extending hole into which the end of a tamping bar may be inserted. In case the stick of 25 dynamite or cartridge containing the primary or detonating cap "hangs up" and the detonating cap pulls out by the friction of the fuse against the wall of the hole it is very likely that the loading bar or tamping 30 bar will accidentally knock the cap against a rock or push it along the side of the wall causing it to explode by friction, thus setting off the entire charge and, of course, blowing the operator to pieces. This accident quite often happens. Dynamite as commonly used 35 is relatively soft, like putty and it is commonly rolled up in an oiled paper wrapper so that the chance of the detonating cap being pulled out of the stick is a very good one.

A further object is to provide a safety cartridge of this character within which the 40 dynamite or other explosive, the cap and the fuse may be readily arranged and disposed.

A still further object is to provide a device of this character so constructed that the 45 cartridge may be readily put in place by the use of a tamping bar without any chance of the tamping bar engaging the cap and detonating it and whereby the cartridge may be readily removed in case of a non-explosion 50 or for any other reason.

Another object is to provide a cartridge of this kind which may be made entirely water-proof, thus eliminating many misfires, saving charges, and avoiding danger.

55 Other objects have to do with the details

of construction and arrangement of parts as will appear more fully hereinafter.

Our invention is illustrated in the accompanying drawings, wherein:—

Figure 1 is a longitudinal sectional view 60 through a cartridge constructed in accordance with our invention;

Figure 2 is an end view of the wooden plug and the adjacent end of the cartridge;

Figures 3 and 4 are fragmentary elevations 65 of the like ends of tamping bars used in connection with our invention;

Figure 5 is a fragmentary section through the rear end of the cartridge and showing 70 the rear end crimped;

Figure 6 is a view illustrating the manner 75 in which the stick of explosive is inserted within the case by means of the fuse.

Referring to this drawing, it will be seen that 10 designates a shell which may be 80 made of cardboard, wood, paper or any other suitable material and which is long enough to contain the stick of dynamite or other explosive and a wooden plug 11. This wooden plug 11 is inserted in and engaged 85 with the paper shell and entirely fills this end of the paper shell. The wooden plug is formed with a longitudinally extending bore 12 which extends from the inner face of the wooden plug at the center thereof longitudinally and outwardly so that the bore merges at the outer end of the plug adjacent the margin thereof. The inner end face of the wooden plug is concave, as at 13, to receive the end of the stick of dynamite 14. 90 The dynamite stick 14 is hollowed at one end to provide a recess for a detonating cap 15 to which a fuse 16 is connected, this fuse passing through the bore 11. The other end of the shell from the plug 11 may be left 95 open or may be closed by crimping inward the paper of the shell, as illustrated in Figure 5, where the shell is crimped, as at 17, over a paper wad or disk 18, or the extremity of the cartridge remote from the plug 11 100 may be covered by a heavy paper cap 19. The end face of the plug 11 at the outer end of the cartridge is formed with a central, longitudinally extending aperture 20 which is preferably tapered at its inner end.

In assembling a cartridge of this character, the fuse 16 is inserted through the bore 12 from the outer end of the cartridge into the interior of the cartridge and through the length of the cartridge. The detonating cap 110

15 is then crimped on the end of the fuse and inserted in the punched end of the stick of dynamite 14. The fuse is now threaded through the opening 12 and the fuse is pulled or the stick 15 pushed into place within the cartridge shell until the stick of powder rests against the concave rear end of the plug 11. The crimped end of the cap 15, it will be understood, cannot pass through the 10 fuse passage 12 and this stick of dynamite comes to rest against the end of the wooden plug 11 with the fuse extending out through the inclined passage 12. The end of the shell is then crimped, as before stated, or 15 covered with a cap 19, as desired, or left entirely open for dry hole shooting, as desired.

The cartridge may be now inserted within the drill hole by using a wooden tamping bar 21 having at one extremity a copper tip or 20 spike 22 having a tapered forward end. This is inserted in the hole 20 and will thus support the dynamite cartridge and the cartridge may be now pushed or tamped into the drill hole. The wooden tamping bar is 25 then withdrawn, the hole closed if necessary, and the cartridge exploded in the ordinary manner. If by any chance the detonating cap 15 is faulty or for any reason the shot should fail and it is designed to remove the 30 charge from the hole, a bar like bar 21 but having a screw-threaded tip 23 (see Figure 4) may be inserted within the hole 20 and rotated to engage the screw with the wooden plug. The cartridge may be then readily 35 withdrawn from the drill hole without any danger.

One of the advantages of this invention resides in the fact that the detonating cap is 40 protected from accidental detonation by a three-inch block or plug of wood 11 so that there is no danger of the cap coming in contact with the walls of the drill hole and thus being prematurely exploded either on inserting the cap into the drill hole or removing the cap therefrom. Furthermore, this wooden plug 11 provides means whereby the cartridge may be readily and safely inserted into the drill hole or removed therefrom. While we have referred to the plug 11 as being 45 of wood, it obviously might be made of compressed paper or any other suitable material. Preferably the cartridge will be made of paraffined pasteboard or paper but we do not wish to be limited to this. If 50 the end of the paper cartridge is crimped, as shown in Figure 5, or a waxed cap is used and passage 12 is greased or waxed, a water-proof cartridge is provided which will eliminate many misfires, thus saving powder 55 and avoiding danger. The paper shell is engaged with the wooden plug by gluing the plug to the shell or by crimping the paper shell to the plug or by some other means which will permanently engage the plug to 60 the paper shell.

It is to be understood that this cartridge which we have described is particularly intended for use where dynamite is used and for use where the holes drilled in the rock are ragged and irregular, thus rendering it 70 necessary to force the dynamite into the back of the hole and not allow it to lodge against projections or drop into pockets. Under these circumstances it is necessary to load the whole charge, frequently running up to 75 two or more cases, one cartridge at a time on a spike in the end of a tamping bar. The chief danger of this operation comes in loading the primer and it is this primer cartridge which forms the subject matter of the 80 present application. If the blasting cap in this primer cartridge is not properly placed but is so disposed that the end of the cap is very close to the surface of the cartridge, 85 there is danger that friction between the side of the cartridge and a boulder in the bore hole may explode the cap and there is particular danger that the copper spike in the tamping bar may strike the cap and thus set off the cartridge 90 prematurely. The safety container or cartridge which we have devised practically eliminates these hazards particularly when ammonia dynamite and a number 8 95 cap is employed as a cartridge of ammonia dynamite is more likely to break or crumble in the loading than is gelatine dynamite. Furthermore the longer shell used with the number 8 cap is more likely to take a diagonal position in the primer than is a shorter 100 cap and is more likely to be struck by the spike on the tamping bar. Besides protecting the primer from rubbing against the bore hole, the container or cartridge also has a waterproofing value as the cardboard 10 tubes are paraffined and if desired, a waterproofing compound can be placed in the container before sliding the primer cartridge into place, thus making a seal between the wooden plug and the primer itself. 11

We claim:

1. An explosive cartridge of the character described comprising an outer shell, a relatively long rigid plug disposed in and permanently engaged with one end of the shell 11 and having a passage for a fuse, a mass of explosive material disposed within said shell behind the plug, and a detonating cap disposed in one end of the mass of explosive material and having a fuse extending out 12 through said fuse passage.

2. An explosive cartridge of the character described comprising an outer shell, a relatively long rigid plug disposed in and permanently engaged with one end of the shell 12 and having a passage for a fuse, a mass of explosive material adjacent the plug end of the cartridge disposed within said shell behind the plug, and a detonating cap disposed in one end of the mass of explosive 13

material adjacent the plug end of the cartridge and having a fuse extending out through said fuse passage to one side of the center thereof, the center of the plug having 5 a longitudinally extending bore adapted to receive the tip of a guiding bar.

3. An explosive cartridge of the character described comprising a shell, a rigid plug disposed in and permanently connected to 10 one end of the shell and extending some distance therealong, said plug having a passage extending from a central point at the inner end of the plug outwardly and longitudinally to a point adjacent the margin 15 of the plug, the center of the plug at its outer end being provided with a longitudinally extending hole, a mass of explosive material disposed within the shell and against the plug, a cap embedded in said mass adjacent 20 the plug and having a fuse extending

from the mass and extending through the passage, and a closure over the opposite extremity of the shell.

4. As an article of manufacture, a cartridge case for high explosives having at 25 one end a solid member inserted in and permanently engaged with the cartridge case, said member being formed with a longitudinally extending hole, opening upon the end of the member and adapted to receive a pin 30 on the end of a tamping bar, the solid member having a fuse, passage extending longitudinally through it and opening upon the end of the solid member to one side of said hole. 35

In testimony whereof we hereunto affix our signatures.

PATRICK T. McLAUGHLIN.
WILLIAM ANDERSON.
